ABSTRACT

Primary Examiner—Huynh D. Le

(74) Attorney, Agent, or Firm—Nixon Peabody LLP

ABSTRACT

Method and apparatus are disclosed for damping the resonance frequency in a microphone. The method and apparatus of the invention involve providing an elastomeric frame to support the backplate. The elastomeric frame forms a substantially air tight seal around the backplate. A hole is formed in the backplate and a cover having an opening therein is placed over the hole in the backplate. The frequency response of the microphone may then be controlled by precisely controlling the size, shape, and/or location of the opening in the cover overlaying the hole. The cover may also serve as an electrical contact to other components in the microphone.

FIG. 3

MICROPHONE WITH INTERNAL DAMPING

FIELD OF THE INVENTION

The present invention relates to miniature microphones used in listening devices, such as hearing aids. In particular, the present invention relates to a method and apparatus for damping the frequency response in such miniature microphones.

BACKGROUND OF THE INVENTION

A conventional listening device such as a hearing aid includes, among other things, a microphone and a receiver. The microphone receives sound waves and converts the sound waves to an audio signal. The audio signal is then processed (e.g., amplified) and provided to the receiver. The receiver converts the processed audio signal into an acoustic signal and subsequently broadcasts the acoustic signal to the user.

The microphone generally has a rigid, electrically charged backplate and a moveable metallic diaphragm. The diaphragm divides the inner volume of the microphone into a front volume and a rear volume. Sound waves enter the microphone via a sound inlet and pass into the front volume. The air vibrations created by the entering sound waves cause the metallic diaphragm to move, thereby inducing an electric signal in the electrically charged backplate corresponding to the sound waves. The electric signal is then processed by audio processing circuitry connected to the charged backplate and converted into an audio signal.

For certain applications, including hearing aids and other listening devices, it is desirable to dampen the resonance frequency of the microphone system. One way to dampen the frequency response is to increase the inertance presented to the sound waves entering the microphone by placing an obstruction near the sound inlet in the front volume. Common types of obstructions include a damping screen made of a grid-like mesh material placed over the sound inlet, a shaped embossment or structure formed or placed inside the housing of the microphone near the sound inlet, and the like.

A damping screen, however, can become clogged as debris and foreign material accumulate on its surface. As the damping screen becomes increasingly clogged, the microphone's frequency response may depart from the specification. A shaped structure can also become less effective as debris accumulates, since the shaped structure depends on its shape to create the desired dampening effect. If the accumulated debris alters the shape of the shaped structure, the microphone's frequency response will be altered. In both of the above cases, the accumulation of debris, such as dust, hairspray, pollen, and other particles, may adversely affect the frequency response of the microphone and may even cause it to malfunction.

Unlike the front volume, the rear volume is typically sealed off and largely impervious to debris. Therefore, some microphones place the damping mechanism in the rear volume to avoid debris accumulation. These microphones use a damping frame between the diaphragm and the backplate to dampen the frequency response. The damping frame has inner slits cut into its opposing edges that, together with the backplate, define apertures through which air may escape from the area between the diaphragm and the backplate to the rest of the rear volume. The escaping air results in a damping of the frequency response of the microphone. An example of such a microphone may be found in commonly-owned U.S. Published Application No. 20030063768 to Cornelius et al., which is incorporated herein by reference in its entirety.

The dimensions of the inner slits in the above microphones have to be very precise in order to achieve the desired level of escaping air for damping purposes. Also, the damping frame is normally made of a stiff or rigid material, usually plastic or Kapton®. Moreover, a hole is sometimes punched through the backplate to facilitate handling during assembly of the microphone. This hole has to be subsequently filled (e.g., with adhesive or similar material) in order to prevent air from escaping through the hole. Accordingly, what is needed is an improved way to control the frequency response of the microphone.

SUMMARY OF THE INVENTION

15 The present invention is directed to a method and apparatus for damping the resonance frequency in a microphone. The method and apparatus of the invention involve providing an elastomeric frame to support the backplate. The elastomeric frame forms a substantially air tight seal around the backplate. A hole is formed in the backplate and a cover having an opening therein is placed over the hole in the backplate. The frequency response of the microphone may then be controlled by precisely controlling the size, shape, and/or location of the opening in the cover overlaying the hole. The cover may also 20 serve as an electrical contact to other components in the microphone.

In general, in one aspect, the invention is directed to a microphone. The microphone comprises a housing, a diaphragm mounted in the housing, and a backplate mounted in the housing at a known location relative to the diaphragm. An electrical-contact element is provided for carrying signals from the backplate, the electrical-contact element providing an acoustic feature for controlling a frequency response of the microphone.

35 In general, in another aspect, the invention is directed to a method of manufacturing a microphone, the microphone having a housing, a diaphragm, and a backplate. The method comprises the steps of lancing a hole through the backplate and surrounding the backplate with a support frame. The support frame forms a substantially airtight seal around the backplate and keeps the backplate centered over the diaphragm. In one embodiment, the support frame also keeps the backplate substantially parallel to and spaced apart from the diaphragm. The method further comprises the step of covering 40 up the hole in the backplate with a cover, the cover having an interior wall defining an opening of a predetermined size, shape, and/or location to control a frequency response of the microphone.

45 50 In general, in yet another aspect, the invention is directed to a mechanism for damping a frequency response of a microphone. The mechanism comprises a backplate mounted in the microphone, the backplate having an inner wall defining a hole through backplate. The mechanism further comprises a cover covering up the hole in the backplate, the cover having an interior wall defining an opening through the cover, the opening having a predetermined size, shape, and/or location for allowing air to escape through the opening.

55 In general, in still another aspect, the invention is directed 60 to a method of damping a frequency response of a microphone, the microphone having at least a housing, a diaphragm mounted in the housing, and a backplate mounted in the housing at a known location relative to the diaphragm. The method comprises the steps of creating at least one hole through the backplate and covering up the at least one hole with a cover such that at least one opening having a predetermined size, shape, and/or location remains over the at least 65

one hole. The frequency response of the microphone is damped based on the predetermined size, shape, and/or location of the at least one opening.

In general, in yet another aspect, the invention is directed to a microphone. The microphone comprises a housing, a diaphragm mounted in the housing, and a backplate mounted substantially parallel to and spaced apart from the diaphragm. The backplate has at least one hole through it. A cover covers up the at least one hole in the backplate. The cover has at least one opening through it, the at least one opening having a predetermined size, shape, and/or location to control a frequency response of the microphone.

The above summary of the present invention is not intended to represent each embodiment, or every aspect, of the present invention.

BRIEF DESCRIPTION OF THE DRAWINGS

The foregoing and other advantages of the invention will become apparent upon reading the following detailed description and upon reference to the drawings, wherein:

FIGS. 1A and 1B illustrate a prior art microphone;

FIGS. 2A-2C illustrate a microphone according to some embodiments of the invention; and

FIG. 3 illustrates another microphone according to some embodiments of the invention.

While the invention is susceptible to various modifications and alternative forms, specific embodiments have been shown by way of example in the drawings and will be described in detail herein. It should be understood, however, that the invention is not intended to be limited to the particular forms disclosed. Rather, the invention is to cover all modifications, equivalents, and alternatives falling within the spirit and scope of the invention as defined by the appended claims.

DESCRIPTION OF ILLUSTRATIVE EMBODIMENTS

As mentioned above, embodiments of the invention provide a method and apparatus for damping the frequency response in a microphone of a listening device, such as a hearing aid. The method and apparatus of the invention makes use of a hole in the backplate by partially covering the hole to control the frequency response. A substantially airtight seal is formed between the backplate and a frame supporting the backplate to prevent air from escaping through the seal.

A prior art microphone 100 for a conventional listening device is shown in FIGS. 1A-1B. Referring first to the perspective view of FIG. 1A, the microphone 100 includes a housing 102 that houses the audio components inside the microphone 100. The housing 102 may be of a size and shape that allows the microphone 100 to be used in miniature listening devices, such as hearing aids. A sound inlet 104 in the housing 102 enables sound waves to enter the microphone 100.

FIG. 1B is a top cut away view of the microphone 100 in FIG. 1A, showing a backplate 110 mounted to a damping frame 112. The rigid, electrically charged backplate 110 is, in some cases, attached to the damping frame 112 by drops of cured adhesive 114 at the corners of the backplate 110. Inner slits 106 defined by the recessed areas 116 in the damping frame 112, are cut out of opposing sides of the damping frame 112 to allow the passage of air therethrough for damping purposes. A hole, defined by the inner wall 118 of the backplate 110, is punched near the middle of the backplate 110 to facilitate handling thereof during assembly of the micro-

phone 100. The hole is subsequently filled in with adhesive and the like to prevent air from escaping through the hole.

FIGS. 2A-2C illustrate a microphone 200 according to embodiments of the invention. As can be seen in FIG. 2A, the microphone 200 is similar to the microphone 100 shown in FIGS. 1A-1B in that it has a housing 202, an inlet port 204a over which a sound inlet (not shown) may be attached. Also present (FIG. 2B) are a diaphragm 206 and a diaphragm support structure 208 for supporting the diaphragm 206. The diaphragm 206 divides the housing 202 of the microphone 200 into a front volume containing the inlet port 204a (FIG. 2A), and a rear volume containing a rigid, electrically charged backplate 210. The backplate 210 is supported by a backplate support frame 212 that keeps the backplate 210 centered over the diaphragm 206.

The backplate support frame 212, unlike the plastic or Kapton® damping frame 112 (see FIGS. 1A-1B), is made of an elastomeric material, such as rubber, silicon, and the like. The elastomeric material of the backplate support frame 212 forms a substantially airtight seal around the backplate 210 that helps prevent air from escaping between the backplate support frame 212 and the backplate 210. This allows the frequency response of the microphone 200 to be more precisely controlled, resulting in higher quality and better manufacturing yields. In some embodiments, the elastomeric material of the backplate support frame 212 is sufficiently rigid to keep the backplate 210 substantially parallel to and spaced apart from the diaphragm 206. Alternatively, or in addition, spacers (not expressly shown) may be used in some implementations to keep the backplate 210 substantially parallel to and spaced apart from the diaphragm 206. The spacers may be, for example, Kapton® bumps commonly known to those having ordinary skill in the art, although any type of spacer may be used without departing from the scope of the invention.

In some embodiments, the backplate support frame 212 may be in the form of an O-ring surrounding the outer circumference of the backplate 210. This may be better viewed in FIG. 2B, which is a cross-section of the microphone 200 along line 2B-2B. As can be seen, the O-ring/backplate support frame 212 is flushed against the outer circumference of the backplate 210 to form an airtight seal. Note that the two components are flushed against each other, but do not overlap in this embodiment. In other embodiments, however, it is possible for the backplate 210 to extend under and/or over and/or into the backplate support frame 212 without departing from the scope of the invention. Further, no slits are cut into the inner edges of the backplate support frame 212, since the present invention uses a different mechanism to dampen the frequency response of the microphone 200, discussed below.

In accordance with embodiments of the invention, the backplate 210 has a hole formed therein, defined by an inner wall 216 of the backplate 210. The hole is located in the middle of the backplate 210 and preferably has a generally round shape, although the particular shape and location of the hole is not overly important to the practice of the invention. As such, the hole may be formed using any suitable means, including by poking or lancing the backplate 210. The shape of the hole may then be reworked if needed. The poking or lancing, however, may result in formation of a stub 218 protruding upward from the backplate 210. With prior art microphones, the stub 218 is not used at all and the hole is used merely to facilitate handling of the backplate 210 and is normally filled in afterwards. In the present invention, however, the hole is left opened to help dampen the frequency

response of the microphone 200. In some embodiments, the stub 218 is also used, as will be described below.

To control the frequency response of the microphone 200, the amount of air allowed to escape through the hole in the backplate 210 needs to be carefully controlled. Therefore, a foil or cover 220, which may be a metal or plastic cover, is placed over the hole in the backplate 210. The foil or cover 220 may reside on either side of the backplate 210, but is preferably on the side facing away from the diaphragm 206. At least one slit or opening is formed in the foil or cover 220, as defined by the interior wall 222, that is smaller than the hole in the backplate 210. This smaller slit or opening consequently limits the amount of air escaping through the backplate 210 and, hence, the frequency response of the microphone 200. The size, shape, location, and/or number of slits or openings may be determined using any suitable technique known to those having ordinary skill in the art, including by trial and error. The desired amount of frequency response damping may then be achieved by precisely following the determined size, shape, location, and/or number of the slit or opening in the foil or cover 220.

To keep the foil or cover 220 in place on the backplate 210, in some embodiments, a lug 224 may be formed on the foil or cover 220. The lug 224 is then braced against the stub 218 to anchor the foil or cover 220 in place on the backplate 210. Any suitable means may be used to form the lug 224, including by poking or lancing the foil or cover 220. Both the lug 224 and the stub 218 may need to be trimmed for optimal efficacy. It is also possible, for example, to glue or weld the foil or cover 220 to the backplate 210 to secure the foil or cover 220 to the backplate 210. In these latter embodiments, the lug 224 is not needed.

In some embodiments, the foil or cover 220 may further include a clip portion 226 extending from one end of the foil or cover 220 away from the backplate 210 at an upward angle. The upward angle may be less than 90°, in which case the clip portion 226 extends over the foil or cover 220, or it may be greater than 90° (but less than 180°), in which case the clip portion 226 does not extend over the foil or cover 220. In either case, the upward angle of the clip portion 226 gives the foil or cover 220 a spring-like effect, pressing against the other components (e.g., a circuit board) on top of the foil or cover 220 when the housing 202 is closed to keep the foil or cover 220 in place on the backplate 210.

In some embodiments, the clip portion 226 also serves as an electrical contact between the backplate 210 and other components in the microphone 200, like a circuit board (not shown). In existing microphones, some type of electrically conductive wire connects the backplate to the circuit board. The wire carries the electric signals induced in the backplate to the circuit board and is usually attached (e.g., soldered) to the circuit board. In the present invention, however, the electrical contact between the backplate 210 and the circuit board may be provided by the spring-like effect of the clip portion 226 pushing against the circuit board. Preferably, the foil or cover 220 and the clip portion 226 are made of a metallic material that is the same as or similar to the material of the backplate 210 for improved electrical contact.

As mentioned above, spacers may be used to keep the backplate 210 substantially parallel to and spaced apart from the diaphragm 206. FIG. 2C illustrates a cross-section of the microphone 200 in which exemplary spacers 228 (e.g. Kapton® bumps) are used. The spacers 228 are disposed between the backplate 210 and the diaphragm 206, and rest on diaphragm support structures 208a, which have been horizontally extended here relative to their counterparts in FIG. 2B. In addition, some embodiments may include standoffs or pro-

trusions (not expressly shown) formed under the diaphragm support structures 208a and extending to the floor of the housing 202 for supporting the diaphragm support structures 208a.

Although the backplate 210 has been shown and described with a single hole through it, the invention is not to be limited thereto. For example, in one embodiment, it is possible to have multiple holes punched through the backplate 210. Then, at least one slit or opening may be formed in the foil or cover 220 over each hole in the backplate 210, with each slit or opening preferably smaller in size than its corresponding hole. It is also possible, of course, to have a single slit or opening in the cover 220 overlapping multiple holes in the backplate 210 without departing from the scope of the invention.

FIG. 3 is a perspective view of another microphone 300 according to embodiments of the invention. As can be seen, the microphone 300 is essentially identical to the microphone 200 of FIGS. 2A-2C in that it includes a housing 302, a sound inlet (not shown), a diaphragm 306, and a diaphragm support structure 308 for supporting the diaphragm 306. Also present are a rigid, electrically charged backplate 310 and an elastomeric backplate support frame 312 for supporting the backplate 310. The backplate 310 has a hole formed therein, as defined by an inner wall 316 thereof, and a stub 318 adjacent to the hole. A foil or cover 320 having a slit or opening therein, as defined by an interior wall 322, covers the hole in the backplate 310. However, unlike the previous embodiments, the foil or cover 320 here is recessed within the backplate 310 (i.e., co-planar with) instead of residing on the backplate 310. This arrangement allows the foil or cover 320 to be simply snapped into place and may result in more consistent positioning of the foil or cover 320 in the backplate 310.

In some embodiments, the foil or cover 320 may further include a backing 324. The backing 324 may be buttressed against the stub 318 to anchor the foil or cover 320 to the backplate 310. Although not expressly shown, a similar backing 324 may be used to secure the foil or cover 220 in the embodiment of FIGS. 2A-2C (i.e., the backing 324 is not specific to any embodiment).

An upwardly angling clip portion 326, similar to the clip portion 226 of FIGS. 2A-2C, may be provided. As before, the clip portion 326 imparts a spring-like effect to the foil or cover 320 that, in some embodiments, helps maintain electrical contact between the backplate 310 and other components, such as a circuit board (not shown), in the microphone 300.

Advantages of the above embodiments include a single foil or cover 220/320 in a microphone 200/300 that can be used both to control the frequency response of the microphone 200/300 as well as to establish an electrical connection between the backplate 210/310 and other components in the microphone. The electrical connection is established and maintained based on the spring-loaded physical contact 20 (i.e., no wire attachment to the circuit board is necessary), which make it easier to assemble the microphone 200/300. In addition, in some embodiments, the foil or cover 220/320 is also self-anchoring in that it keeps itself secured to the backplate 210/310 by virtue of being spring-loaded.

Moreover, the use of a separate component 220/320 to control the frequency response of the microphone 200/300 allows the microphone to be modular. Thus, the same diaphragm 206/306, backplate 210/310, along with the supporting structures 208/308/212/312 therefor, may be used for all microphones, and only the foil or cover 220/320 need vary. As a result, large variations may occur in the size and/or shape of the hole in the backplate 210/310 without affecting the manufacturability of the microphones. This allows manufacturers

to pick and choose the desired level of damping by simply selecting a foil or cover 220/320 with a certain size opening.

While the present invention has been described with reference to one or more particular embodiments, those skilled in the art will recognize that many changes may be made thereto without departing from the spirit and scope of the present invention. Each of these embodiments and obvious variations thereof is contemplated as falling within the spirit and scope of the claimed invention, which is set forth in the following claims.

What is claimed is:

1. A microphone, comprising:

a housing;

a diaphragm mounted in said housing;

a backplate mounted substantially parallel to and spaced apart from said diaphragm, said backplate having at least one hole through said backplate; and

a cover contacting a surface portion of said backplate to cover up said at least one hole in said backplate, said cover having at least one opening through said cover, said at least one opening having a predetermined size, shape, and/or location to control a frequency response of said microphone, said at least one opening being smaller than said at least one hole, said cover having a footprint that is less than a footprint of said backplate, wherein said cover includes a clip portion extending away from said backplate at an angle, said clip portion providing a spring-load for said cover.

2. The microphone according to claim 1, further comprising a support frame surrounding a circumference of said backplate, said support frame forming an airtight seal with said backplate.

3. The microphone according to claim 2, wherein said support frame is made of an elastomeric material.

4. The microphone according to claim 3, wherein said elastomeric material includes rubber and silicon.

5. The microphone according to claim 1, wherein said cover resides within said backplate.

6. The microphone according to claim 1, wherein said cover resides on top of said backplate.

7. The microphone according to claim 1, wherein said at least one opening in said cover has a substantially rectangular shape.

8. The microphone according to claim 7, wherein said clip portion provides an electrical connection between said backplate and other components in said microphone.

9. The microphone according to claim 1, wherein said backplate includes a stub protruding from said backplate and said cover includes a lug formed therein, said lug braced against said stub to help keep said cover in place.

10. The microphone according to claim 1, wherein said backplate includes a stub protruding from said backplate and said cover includes a backing formed thereon, said backing buttressed against said stub to help keep said cover in place.

5 11. The microphone according to claim 1, wherein said cover is adhered to said backplate to help keep said cover in place.

12. The microphone according to claim 11, further comprising a substantially airtight seal around said backplate.

10 13. The microphone according to claim 11, wherein said cover is wedged on said backplate.

14. The microphone according to claim 11, wherein said cover is fitted into said backplate.

15 15. The microphone according to claim 1, wherein said cover is welded to said backplate to help keep said cover in place.

16. The microphone according to claim 1, wherein said cover includes a metallic material.

20 17. The microphone according to claim 1, wherein said cover includes plastic.

18. A microphone, comprising:

a housing;

a diaphragm mounted in said housing;

a backplate mounted in said housing at a known location relative to said diaphragm, said backplate having a hole through said backplate;

25 an electrical-contact element contacting a surface portion of said backplate for carrying signals from said backplate, said electrical-contact element providing an opening having a predetermined size, shape, and/or location in said electrical-contact element for controlling a frequency response of said microphone, said opening being smaller than said hole, wherein said electrical-contact element includes a clip portion extending away from said backplate at an angle, said clip portion providing a spring-load for said electrical-contact element and an electrical connection between said backplate and other components in said microphone, and wherein said electrical-contact element has a footprint that is less than a footprint of said backplate.

30 19. The microphone according to claim 18, wherein said predetermined shape of said opening is substantially rectangular.

35 20. The microphone according to claim 18, wherein said electrical-contact element resides on said backplate.

40 21. The microphone according to claim 18, wherein said electrical-contact element is recessed into said backplate.
